(57) CLAIM

The ornamental design for a stowable display system with video player, substantially as shown and described.

DESCRIPTION

FIG. 1 is a perspective view of the stowable display system with video player in accordance with the present invention, with the display being depicted in a stowed orientation; FIG. 2 is a top view thereof with the display in the stowed orientation;

FIG. 3 is a right-side view thereof with the display in the stowed orientation;

FIG. 4 is a front view thereof with the display in the stowed orientation;

FIG. 5 is a rear view thereof with the display in the stowed orientation; and,

FIG. 6 is a perspective view thereof with the display in a deployed orientation.

The broken lines shown in FIGS. 1-6 are for illustrative purposes as an environment and form no part of the claimed design.
